UNITED STATES PATENT OFFICE.

WILLIAM KEAST, OF RUSSELL GULCH, COLORADO.

PUMP.

SPECIFICATION forming part of Letters Patent No. 394,699, dated December 18, 1888.

Application filed September 20, 1888. Serial No. 285,867. (No model.)

To all whom it may concern:

Be it known that I, WILLIAM KEAST, of Russell Gulch, in the county of Gilpin and State of Colorado, have invented a new and Improved Pump, of which the following is a full, clear, and exact description.

This invention relates to improved valve-operating mechanism to be applied to the suction-box of my new pump shown and described in my allowed application, Serial No. 252,892, filed October 20, 1887.

Reference is to be had to the accompanying drawings, forming a part of this specification, in which similar letters of reference indicate corresponding parts in both the figures.

Figure 1 is a broken perspective view of the suction-box marked P in my said application, showing my improved mechanism for operating the valves to drain the pump; and Fig. 2 is a sectional elevation taken on line x of Fig. 1.

The suction-box P is provided with valves Q R, the same as in my said application, and the box is of substantially the same construction as in my said application, except that it is formed with the side chamber, A, at the top and the opposite side chamber, B, at the bottom, in which the valve-operating rods S² U², chains (or other flexible connections) B' B², and the operating-wheels C C' are placed. The rods S² U² are connected to the wheels by the said chains, and are operated by cords or wires S³ U³, the same as in my above-mentioned application. Each valve is provided with a lateral arm, D, connected to an arm, E, pivoted at one end to and between suitable lugs, a a. The outer free end of each of the piv-

oted arms E is weighted, as at E', to rapidly close the valves. The wheels C C' are pivoted parallel with the arms E, and each 40 wheel is provided with a pin or stud, b, which projects under the adjacent arm and serves to lift it and the valve when the wheel is turned to carry the said pin above the axis of the wheel, as shown in Fig. 2. The operating-cord being relaxed, the valve will drop of its own weight, returning the wheel and parts connected therewith.

By this construction all springs are avoided and the operating-rods, being connected to the 50 wheels by chains, will not be distorted in operation, but will pass always in a straight line through the boxes c at the tops of the side chambers, A B, thus obviating friction.

Having thus described my invention, what I 55 claim as new, and desire to secure by Letters Patent, is—

1. The suction-box P, provided with valves, and wheels having pins engaging with projections on the valves, in combination with 60 the operating-rods connected to the wheels by chains, substantially as described.

2. The suction-box P and valves pivoted therein and attached to the pivoted arms E, in combination with the operating-wheels provided with side projections to engage with the pivoted arms E, and the rods attached to the wheels by flexible connections, substantially as described.

WILLIAM KEAST.
